UNITED STATES PATENT OFFICE.

HARRY E. SEAMAN, OF PHILADELPHIA, PENNSYLVANIA.

LOCOMOTIVE.

1,185,008.

Specification of Letters Patent. Patented May 30, 1916.

Application filed July 1, 1915. Serial No. 37,610.

To all whom it may concern:

Be it known that I, HARRY E. SEAMAN, a citizen of the United States, residing at Philadelphia, in the county of Philadelphia and State of Pennsylvania, have invented 5 certain new and useful Improvements in Locomotives, of which the following is a specification.

My invention relates to improvements in 10 locomotives, and more particularly to improved means for returning a large part of the smoke and gases from the smoke box into the fire chamber to be consumed and not wasted as is generally the case.

15 A further object is to provide an improved construction of petticoat pipe located in the smoke box in line with the exhaust nozzle and blower which operates to divide the smoke and gases causing a portion thereof to escape through the stack, but 20 compelling the greater portion to return to the fire box for consumption.

25 A further object is to provide improved means for controlling the draft of the return of the smoke and gases and admitting air to the returning smoke and gases to facilitate combustion as well as induce the draft.

With these and other objects in view, the 30 invention consists in certain novel features of construction and combinations and arrangements of parts as will be more fully hereinafter described and pointed out in the claims.

35 In the accompanying drawings: Figure 1 is a view in side elevation partly broken away illustrating my improvements. Fig. 2 is a top plan view of Fig. 1. Fig. 3 is an enlarged fragmentary view in longitudinal 40 section on the line 3—3 of Fig. 1. Fig. 4 is an enlarged view in transverse section through the smoke box illustrating my improved construction of petticoat pipe. Fig. 5 is a view in transverse section on the line 45 5—5 of Fig. 4, and Fig. 6 is an enlarged detail sectional view illustrating the arrangement of steam nozzle to induce a draft in the smoke return pipe.

1 represents a locomotive having the ordinary fire box 2 at its rear end and smoke box 3 at its front end.

4 is the smoke stack which is secured in the top of the smoke box in line with the exhaust nozzle 5 and blower 6.

55 7 represents my improved petticoat pipe which is provided at its upper end with a

flange 8 bearing against a flange 9 on the lower end of the stack and secured to the lower end of the stack by bolts 10 as indicated in dotted lines in Fig. 4. 60

My improved petticoat pipe 7 comprises a casting having a central flue 11, and two outer flues 12. These outer flues are separated by partition walls 13, and gradually change their shape from semi-cylindrical 65 cross sections into cylindrical nipples 14 which extend through the wall of the smoke box, and are connected by pipes 15 with openings 16 in the rear wall of the fire box.

The central flue 11 gradually increases in 70 diameter until it reaches the full diameter of the stack, but terminates at a point removed from the lower end of the petticoat pipe which lower end is flared outwardly 75 as shown at 17 so as to induce the draft caused by the exhaust from cylinders.

As shown in Fig. 5, the flues 11 and 12 are of substantially the same area in cross section, so that while the center flue 11 receives the direct line of steam from the exhaust, most of the smoke and gases will be forced through the flues 12, and while I do not limit myself to any particular proportion, I believe about eighty per cent. of the smoke and gases will be returned to the fire 80 box, this, of course, resulting in a great saving of fuel which would be otherwise lost, and also reducing to a minimum the discharge of cinders and sparks.

The pipes 15 are provided with air inlet 90 funnels 18 which communicate with openings 19 in the pipes, and the entrances to these funnels are controlled by dampers 20 hinged at one end as shown at 21, and connected by rods 22 with operating hand levers 23, so that they can be moved to open or closed position as desired by the engineer. These dampers are preferably swung inwardly to open them, and allow air to flow into the pipes. This suction of air is induced by the movement of the locomotive, and the air not only increases the draft, but also supplies a certain amount of oxygen which aids in the combustion. The forward or closing movement of the dampers is limited by stops 24 as shown clearly in Fig. 3. 105

As an additional means for controlling or supplying draft, I provide steam nozzles 25 projecting rearwardly in the pipes 15 and connect these nozzles by pipes 26 with the 110 steam supply pipes 27, which supply steam to the blower 6, hence whenever the blower

is operated, the steam is directed rearwardly in the pipes 15, so that by this means the return of smoke and gases can be had while the engine is standing as well as running, 5 and I can admit air or steam, or both, just as may be desired to produce the best results.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a locomotive having a fire box at one end, a smoke box at its other end, a stack in the upper part of the smoke box, and a blower in the lower part of the smoke box in line with the stack, of a petticoat pipe secured to the stack and located in the smoke box, said petticoat pipe 20 divided into a central flue of greatest diameter at its upper end and communicating directly with the stack, and side flues independent of the central flue communicating at their lower ends with the smoke box, and 25 pipes connecting the side flues with the fire box, substantially as described.

2. The combination with a locomotive having a fire box at one end, a smoke box at its other end, a stack in the upper part of the smoke box, and a blower in the lower part of the smoke box in line with the stack, of a petticoat pipe secured to the stack and located in the smoke box, said petticoat pipe 30 divided into a central flue communicating with the stack, said central flue of general cylindrical form throughout its lower portion and increasing in diameter at its upper 35 end to the diameter of the petticoat and secured directly to the stack, and side flues independent of the central flue communicating at their lower ends with the smoke box, and 40 pipes connecting the side flues with the fire box, substantially as described.

45

with the said pipes, and dampers controlling the entrance of air to the funnels, substantially as described. 50

3. The combination with a locomotive having a fire box at one end, a smoke box at its other end, a stack in the upper part of the smoke box, and a blower in the lower part of the smoke box in line with the stack, of a petticoat pipe secured to the stack and located in the smoke box, said petticoat pipe 55 divided into a central flue communicating with the stack, said central flue of general cylindrical form throughout its lower portion and increasing in diameter at its upper end to the diameter of the petticoat and secured directly to the stack, and side flues independent of the central flue, communicating 60 at their lower ends with the smoke box, pipes connecting the side flues with the fire box, and steam nozzles discharging rearwardly in said pipes, substantially as described. 65

4. The combination with a locomotive having a smoke box at one end, and a nozzle and blower in the lower portion of the smoke box, of a petticoat pipe secured to the stack and located in the smoke box of the locomotive, said petticoat pipe comprising a casting having a central flue communicating with the stack, said central flue of general cylindrical form throughout its lower portion and increasing in diameter at its upper 70 end to the diameter of the petticoat and secured directly to the stack, and flues outside of the central flue communicating with the smoke box, said petticoat pipe at its lower end outwardly flared and located in line 75 with the exhaust nozzle and blower in the bottom of the smoke box, substantially as described.

In testimony whereof I have signed my name to this specification in the presence of 80 two subscribing witnesses.

HARRY E. SEAMAN.
